ENVELOPE FEEDING MECHANISM

Abraham Novick, Flushing, N. Y., assignor to
 F. L. Smithe Machine Co., Inc., New York,
 N. Y., a corporation of New York

Application March 11, 1949, Serial No. 80,842

7 Claims. (Cl. 271—62)

1

This invention relates to envelope feeding mechanism and more particularly to mechanism which is designed to act upon envelopes whose manufacture is complete except for the printing.

It is important in connection with the printing operation that the envelopes be advanced in properly timed and spaced relation. Such timing and spacing can be conveniently obtained by the use of a pin conveyor having pins disposed at uniform intervals which are adapted to engage in the corners between the folded over sealing flaps and the envelope backs.

The primary object of the present invention is to provide simple and practical mechanism for delivering envelopes from stack formation to a conveyor of the kind referred to.

In dealing with this problem it is desirable that an envelope be on hand and ready to be carried away each time that a pair of pins of the pin conveyor arrives at the envelope pick-up station. It is not desirable, however, to crowd the envelopes in dense formation toward such station, for then the withdrawal of one envelope would be apt to disarrange one or more of the following envelopes of the stack, either dislodging or skewing the envelopes, and interfering with the proper and orderly automatic operation of the machine.

In accordance with an important feature of the present invention, a stack conveyor is provided which is adapted to be driven at either of two predetermined speeds. While envelopes differ in thickness and the frequency of envelope delivery cannot, therefore, be precisely forecast for either of the predetermined conveyor speeds, the conveyor speeds are so chosen that one of them will cause the envelopes to be delivered at a frequency exceeding the supply requirements of the pin conveyor, while the other will cause the envelopes to be delivered at a frequency less than the supply requirements of the pin conveyor. By switching back and forth between the high and low speeds of the two-speed conveyor, the conveyor is caused to deliver the envelopes at an average frequency corresponding precisely with the supply requirements of the pin conveyor. The control is such that the envelopes are caused to approach the transfer point slowly enough to permit the envelopes at the leading end of the stack to spring apart. This reduces the stack density so that each envelope can be readily picked up without disarranging following envelopes.

For reducing the stack density at the point of delivery to the pin conveyor and for enabling the

2

stack density to be automatically measured and used for controlling the two-speed conveyor in the manner just referred to, a light source is disposed alongside the stack to project light upon and between lower corners of the envelopes as they near the pickup point. A photoelectric cell is arranged to be responsive to the light that passes through a corner of the stack. The intensity of the light is affected by the density of the stack through which the light passes, and the density of the stack depends primarily upon the average frequency of envelope delivery. The photoelectric cell output is amplified and acts through a relay to control mechanism for automatically reducing the speed of the two-speed conveyor when the stack density is greater than that desired, and for automatically increasing the speed of the two-speed conveyor when stack density is less than that desired.

20 The projection of light across a stack corner and the utilization of the transmitted light to control operating mechanism of any kind is believed to be broadly new.

25 Other objects and advantages will hereinafter appear.

In the drawing forming part of this specification

30 Fig. 1 is a view in side elevation, partly diagrammatic, of an illustrative machine embodying features of the invention;

35 Fig. 2 is a view in sectional elevation taken upon the line 2—2 of Fig. 1 in the direction indicated by the arrows, the view being upon a considerably larger scale than Fig. 1;

40 Fig. 3 is a fragmentary plan view showing the delivery end of the stack conveyor and an associated density meter;

45 Fig. 4 is a fragmentary view showing a group of envelopes puffed out as they would be at the delivery end of the stack conveyor, the view being taken upon the line 4—4 of Fig. 2 in the direction indicated by the arrows;

50 Fig. 5 is a fragmentary view showing a group of envelopes in compact formation as they would be throughout most of the length of the stack;

55 Fig. 6 is a fragmentary vertical sectional view of a portion of the transmission mechanism through which the stack conveyor is driven, the view being taken upon the line 6—6 of Fig. 7 in the direction indicated by the arrows;

Fig. 7 is a fragmentary, horizontal sectional view taken upon the line 7—7 of Fig. 6 in the directions indicated by the arrows;

Fig. 8 is a fragmentary, vertical sectional view

taken upon the line 8—8 of Fig. 6 in the direction indicated by the arrows;

Fig. 9 is a fragmentary, vertical sectional view taken upon the line 9—9 of Fig. 6 in the direction indicated by the arrows;

Fig. 10 is a detail sectional view through a roller clutch which forms part of the transmission train through which the stack conveyor is driven;

Fig. 11 is an electrical diagram showing the circuits and electrical mechanism through which the stack conveyor drive is controlled.

The illustrative mechanism comprises a printing roller 1 supplied with ink through transfer rollers 2 and 3 and an impression roller 4. The rollers 1 and 4 are fast upon shafts 5 and 6, respectively, and these shafts also have fast upon them meshing gears 7 and 8 whose pitch diameters are equal to the diameters of the rollers 1 and 4. The shaft 6 also has fast upon it sprockets 9 which are adapted to cooperate with conveyor chains 10 and 11 (Figs. 1 and 2).

The chain 11, which is farther from the observer in Fig. 1, runs upon fixed sprockets 12, 13, 14 and 15 which are fast upon shafts 16, 17, 18, and 19. The chains 10, which are nearer the observer in Fig. 10, run upon sprockets 12a, 13a, 14a and 15a which are mounted with capacity for axial adjustment upon the shafts 16, 17, 18 and 19, respectively. The sprocket 9 nearer the observer in Fig. 1 is also correspondingly adjustable axially of the shaft 6. The chains 10 and 11 are provided at uniform intervals with inwardly reaching fingers 20 and 21.

The chains 10 and 11 are driven from the shaft 16. The shaft 16 is driven from a shaft 22 through a sprocket 23, a chain 24 and a sprocket 25. The shaft 22 is driven at constant speed, and hence the chains 10 and 11 are caused to travel at a constant speed equal to the circumferential speeds of the rollers 1 and 4.

The fingers 20 and 21 are designed to engage at the corners of the leading envelope of a stack 26 between the back and the folded down sealing flap of the leading envelope of the stack, and to pick the leading envelope away from the stack and carry it forward to the printing instrumentalities. Individual envelopes 27, 28, 29 and 30 are shown in Fig. 1 as being carried forward by the pin conveyor.

The envelope stack 26 is shown as supported upon a two-speed conveyor 31 which carries the envelopes in stack formation toward the transfer point at which they are picked up by the pin conveyor. Sucker shoes 32 (Figs. 1 and 2) are provided in the path of the envelopes at the transfer point to free the leading envelope from the stack and keep the envelopes from becoming accidentally disarranged.

The conveyor 31 comprises a pair of chains 33 and 34 which are guided in channel bars 33a and 34a and run upon sprockets 35 and 36 carried by shaft 37 and upon a corresponding pair of sprockets including a sprocket 38 carried by a shaft 39. The sprockets which carry the chain 34 are fixed on their respective shafts 37 and 39, but the sprockets 35 and 38 which carry the chain 33 are adjustable axially on their shafts to change the spacing of the chains 33 and 34 while maintaining the position of the chain 34 uniform.

The envelopes of the stack 26 are for the most part tightly compressed as shown in Fig. 5. If the stack were initially tightly compressed from end to end and the conveyor 31 were advanced

rapidly enough to cause the blanks to arrive at the transfer point as fast as they are taken away by the pin conveyor, the compressed condition of the stack at the leading end thereof would be maintained. If, however, the conveyor 31 is caused to advance the stack so slowly that the envelopes are not delivered as rapidly as they are required by the pin conveyor, the envelopes at the leading end of the stack will tend to spring apart as shown in Fig. 4 as the pressure at the leading end of the stack is relieved. With the envelopes thus separated, they can be conveniently and smoothly picked up by the pin conveyor without frictionally dislodging or disarranging following envelopes of the stack. As soon as this desirable spacing at the forward end of the stack is achieved, however, the average speed of advance of the conveyor 31 must be increased sufficiently to supply the needs of the pin conveyor so that there will not be an accumulating deficiency of blanks at the transfer point.

In order to achieve an operation of the kind referred to, provision is made for measuring the density of the stack as it approaches the transfer point and for maintaining the average speed of the conveyor at a value to assure that the requirements of the pin conveyor will be satisfied without any oversupply. By causing the density meter to shift the stack conveyor drive, speeding up the conveyor 31 when the stack density falls below a desired value and reducing the speed of the conveyor 31 when the density of the stack exceeds a desired value, the desired transfer condition and the desired average speed may be maintained.

The same shaft 22 which drives the printing mechanism and the pin conveyor also drives the conveyor 31. The drive is transmitted through a V-pulley 40 of fixed diameter and a V-belt 41. The belt 41 also runs upon a variable diameter V-pulley 42 which is mounted upon and drives a shaft 43. The V-belt and V-pulleys constitute elements of a conventional, infinitely variable speed drive mechanism. The pulley 42 may, as is well understood, comprise a fixed section 44 and a movable section 45 spring urged toward the section 44.

The pulley 42 and the shaft 43 are carried upon a frame 46, which is adjustable toward and from the shaft 22. Adjustment of the frame away from the shaft 22 increases the tension of the belt 41 and serves to force the pulley section 45 away from the fixed pulley section 44, thereby reducing the effective diameter of the pulley 42 and increasing the drive ratio of the belt and pulley combination. The frame 46 is slidably mounted upon a stationary frame member 47 (Figs. 6 and 9).

The frame 46 comprises upstanding bearing portions 46a and 46b (Figs. 6, 7, 8 and 9) in which certain gears and shafts to be described are mounted, a horizontally disposed base portion 46c and a downwardly extending vertical web portion 46d. The web portion 46d is maintained in contact with a stationary frame member 47, while a part of the base portion 46c rides upon the upper face of the stationary frame member 47. The stationary frame member 47 has a rectangular bar 47a secured to it by screws 47b, whose heads are completely embedded in the bar. The web 46d of the frame 46 is formed with a channel 46e which extends through the web from end to end and slidably receives the stationary bar 47a.

A headed screw 47c has a comparatively large shank portion 47d disposed within a slot 46f of the web 46d and a reduced shank portion 47e extended through an opening 47f of the frame member 47. The screw 47c is drawn tight to clamp the web 46d against the frame member 47 by a nut 47g. A lock nut 47h is provided for retaining the nut 47g in clamping position. In order to permit the frame 46 to be shifted, it is necessary that the nuts 47g and 47h be first loosened. After a new adjustment has been effected, the nuts are again tightened to hold the adjustment.

A threaded rod 48 is screwed into the frame member 46a and is adapted by its rotation to adjust the frame toward and from the shaft 22. The rod 48 is equipped with an operating handle 49. An unthreaded portion of the rod 48 is passed through a bore formed in a bracket member 50, the bracket member being secured upon the stationary frame member 47. Collars 51 pinned to the rod 48 at opposite sides of the bracket 50 prevent the rod from moving longitudinally relatively to the bracket, while permitting it to rotate in the bracket. A set screw 52 threaded through the bracket 50 and having a head 53 which is equipped with arms 54 may be tightened against the rod 48 to lock it in fixed position after an adjustment has been made. This second locking means may be used to supplement the lock provided by screw 47c and nuts 47g and 47h, or in lieu thereof. Either locking means will prevent the frame 46 from shifting accidentally. The purpose of the adjustable speed unit is to enable both speeds of the conveyor 31 to be adjusted relative to the speed of the pin conveyor 35 for different thickness of envelopes.

The shaft 43 is adapted to transmit drive to the conveyor 31 through alternative drive trains. The shaft 43 has fast upon it a worm 55 which drives a worm wheel 56 (Figs. 6, 7 and 9). The 40 worm wheel 56 is supported at one side of a flange 57 formed on a sleeve 58, the sleeve 58 being revolvably mounted upon a shaft 59. Also mounted upon the sleeve 58 at the opposite side of the flange 57 from the worm wheel 56 is a gear 60.

A sleeve 61 is connected to the shaft 59 through a key 62 and held to the shaft by a set screw 63 extends into the space within the worm wheel 56. A disk 64 is mounted upon the sleeve 61 and is secured to the gear 60 by headed screws 65. A ring 66 extends within the worm gear 56 into engagement with the flange 57, and itself includes a circumferential flange 67 which bears against the worm gear 56 in opposition to the flange 57. The screws 65 are passed through disk 64, flange 67, the worm wheel 56, and the flange 57, and are threaded into the gear 60 so that all of these parts travel in unison with one another.

The ring 66 constitutes the outer, driving element of a roller clutch. The sleeve 61 constitutes the inner, driven element of the roller clutch. The sleeve 61 is formed with notches 68 (Fig. 10) in which rollers 69 are received, the rollers being urged outward by compression coil springs 70.

As seen in Fig. 10, the worm wheel 56 is constantly driven in a counter-clockwise direction and transmits drive through the roller clutch to the shaft 59, so long as the shaft 59 is not driven independently of the ball clutch at a greater rotary speed than the rotary speed of the worm wheel 56.

The shaft 59 is connected through a universal joint 71 (Fig. 6) with a sleeve 72 which forms the outer element of a telescoping transmission shaft. The inner element 73 is connected through a key

74 and a slot 75 with the outer element 72. The member 73 is connected through a universal joint 76 (Figs. 1 and 2) with a shaft 77.

The shaft 77, journaled in a frame bracket 78, has fast upon it a worm 79. The worm 79 drives a worm wheel 80 which is made fast with a gear 81, the worm wheel and a gear combination being revolvably mounted upon a shaft 82 which is supported in the bracket 78. A collar 83 pinned to the shaft 82 maintains the gear 81 and the worm wheel 80 in place upon the shaft. The gear 81 drives a gear 84 which is fast upon the drive shaft 37 of the stack conveyor 31 to rotate said shaft in the direction indicated by the arrow in Fig. 2.

The drive train which has been described provides a relatively slow drive of the stack conveyor 31 which is not intended to deliver envelopes rapidly enough to supply the requirements of the pin conveyor.

The alternative drive train goes from the gear 60 to a gear 85 fast upon a shaft 86 (Figs. 7 and 9). The shaft 86 also has fast upon it a gear 87 which drives a long-toothed gear 88. The gear 88 forms one element of a toothed clutch 89. The gear 88 is freely revolvable upon the shaft 59 and is confined between frame member 46b and a shoulder 90 of the shaft 59 and rotates idly while the shaft 59 is being driven by the above described roller clutch.

The toothed clutch face of the gear 88 is adapted to cooperate with a complementary shiftable clutch member 91. The clutch member 91 is mounted upon the larger portion of the shaft 59 and is connected to it through a key 92 formed on the shaft. The clutch member 91 is formed with a circumferential groove 93 for cooperation with a fork 94 through which the clutch member is controlled and shifted.

The fork member 94 comprises a rock shaft 95 having upwardly extending parallel arms 96 and 97, each arm including at its upper end an inwardly reaching finger or roller 98, which extends into the groove 93. The frame member 46a carries brackets 99 in which bearing pins 100 are mounted and secured by set screws 101. The bearing pins 100 extend into bores formed in the opposite ends of the rock shaft 95 to support the shaft with capacity for rocking movement. A downwardly extending arm 102 of the rock shaft is connected through a tension spring 103 to an ear 104 of the frame member 46b. A set screw 103a serves as a stop for the arm 97 of fork 94 to arrest the latter in its normal position against the action of spring 103. The spring tends to shift the clutch member 91 out of engagement with the clutch face of the gear 88 and thereby to render the second train ineffective to drive the shaft 59.

A laterally extending arm 105 of the rock shaft 95 is connected through a link 106 with the armature 107 of an electromagnet 108 secured by studs or bolts 108a to the web portion 46d of the frame 46 and which will be described and explained 65 fully at a subsequent point in this specification. When the armature 107 is drawn downward, the rock shaft 95 is rocked clockwise as viewed in Fig. 6 to carry the clutch member 91 into engagement with the clutch face of the gear 88. When this occurs, the second train is made effective to drive the shaft 59 at a considerably higher speed than that at which it is driven through the slip clutch train. The roller clutch (Fig. 10) permits the shaft 59 with its sleeve 61 to rotate faster than the worm wheel 56.

In the illustrative structure, the multiplying train, comprising gears 69, 85, 87 and 88, drives the shaft 59 at approximately three times the speed at which the shaft is driven from the worm wheel 56 through the slip clutch. Whenever the toothed clutch member 91 is engaged to make the second train effective, therefore, the shaft 59 simply turns faster than, or in other words overruns the worm 56, so that the slip clutch train becomes ineffective. As soon as the clutch member 91 is disengaged, however, the fast train is rendered ineffective and the slip clutch immediately and automatically resumes the driving of the shaft 59.

From what has been said it will be apparent that in the illustrative mechanism the conveyor 31 is always driven, but that it is driven at two speeds one of which is three times as great as the other. By controlling the time apportioned to the two drive trains the average speed of the conveyor 31 can be made to have any value between the higher speed and the lower speed. In order that the average speed shall exactly meet the requirements of the pin conveyor, the drive mechanism is controlled from the stack itself, and in such manner that the envelopes will be uncompressed as they near the transfer point.

For regulating the average rate of envelope feed and controlling the stack density, a density meter is provided. The density meter comprises a light 109 (Figs. 2, 3 and 11) and a reflector 110 disposed to project light downward across a corner of the stack near the transfer point. A portion of the light, whose intensity depends upon the density of the envelopes upon the conveyor 31, passes through a slot 111 in the casing 112 of a photoelectric cell 113. The light is reflected by a reflecting surface 114 upon the cathode 115 of the photoelectric cell. This causes a feeble electric current to be generated whose potential is a function of the intensity of the light which falls upon the cathode 115. The output of the photoelectric cell is utilized for controlling the operation of the electromagnet 108.

The photoelectric cell 113 and the amplifier tube 116 receive their plate voltages from bleeder resistor 119. The bleeder resistor is supplied through conductors 117 and 118. The photoelectric cell is connected to supply grid voltage to the amplifier tube 116. One lead 120 runs from the photoelectric cell to the grid of the tube 116, while the other lead 121 is adjustably connected to the resistor 119. The resistor 119 is connected to the cathode of the tube 116 through a conductor 122. The conductors 120 and 122 are connected to one another through a resistor 123.

The plate circuit of the tube 116 includes a conductor 124 which is connected to the conductor 118 through a fixed resistor 125. The conductor 124 is connected through a resistor 126 to the grid of a thyatron 127. The conductor 118 is connected to the cathode of the thyatron 127 through conductors 128 and 129. When the bias of the thyatron grid as controlled from the photoelectric cell attains a predetermined value, the thyatron is tripped and will thereafter pass current from its cathode to its plate so long as a potential tending to cause current to flow in that direction is uninterruptedly maintained, even though the grid bias should subsequently fall below the value which was required to trip the thyatron in the first place.

Conductors 130 and 131 supplied from a commercial source of alternating current are connected to the primary 132 of a transformer 133.

The secondary 134 of the transformer 133 has one of its ends connected through a conductor 135 with the conductor 129 which runs to the cathode of the thyatron 127. The plate of the thyatron is connected through a conductor 136 with a D. C. relay coil 137, and the circuit is completed from the relay coil 137 to the secondary 134 through a conductor 138.

The tendency of the transformer 133 is to cause alternating current to flow in the thyatron circuit. Since the thyatron will pass current in only one direction, however, alternate half cycles are passed, while the other alternate half cycles are suppressed. The current that flows through the relay coil 137 is, therefore, direct but intermittent current. The relay armature consists of a switch member 139, and this is made slow acting enough to remain in its closed position during the half cycles in which the relay coil is unenergized. Because of the fact, however, that during alternate half cycles the flow of current in the thyatron circuit is interrupted, it is necessary for maintaining the switch 139 in a closed condition that the thyatron grid shall trip off the thyatron at the beginning of each active half cycle. Thus at any time when the thyatron grid bias falls below a predetermined tripping value, the positive half cycles as well as the negative half cycles will be suppressed by the thyatron, and the switch 139 will be permitted to open. The switch 139 is designed to control the electromagnet 108 which is of the alternating current type. The circuit of electromagnet 108 may be traced out from the conductor 130 through a conductor 140, switch 139, conductor 141, electromagnet 108 and conductor 142, back to the conductor 131.

It will now be apparent that the clutch member 91 is controlled from the photoelectric cell, and that the effect of the photoelectric cell is determined by the stack density. When stack density exceeds a predetermined value, the light transmitted to the cathode 115 of the photoelectric cell is of low intensity, the resulting bias transmitted to the thyatron grid is low, the thyatron circuit is not tripped, and the switch 139 remains open so that the electromagnet 108 is not energized. The spring 103 accordingly acts to maintain the clutch member 91 out of engagement with the clutch face of the gear 88, so that the low speed drive of the conveyor 31 is maintained effective and the high speed drive is maintained ineffective.

Since the low speed drive is not capable of meeting the requirements of the pin conveyor, the density of the stack near the transfer point will after a time be diminished and more light will be transmitted to the cathode 115 of the photoelectric cell. At a desired stack density value, the intensity of this light will be sufficient to cause the thyatron to be tripped. The high speed drive for the stack conveyor 31 will thereupon be made effective, and this if maintained long enough would fully recompress the envelopes. As soon as the stack density is increased from above the desired critical density, however, the intensity of the transmitted light is again reduced to the point where the thyatron can no longer be tripped. It is evident, therefore, that the described mechanism will control the stack feed so as to maintain the average rate of envelope delivery exactly equal to the requirements of the pin conveyor and the stack density adjacent the transfer point at a desired value which enables the envelopes to be detached one by one.

from the stack without dislodging or disarranging adjacent envelopes of the stack.

I have described what I believe to be the best embodiments of my invention. I do not wish, however, to be confined to the embodiments shown, but what I desire to cover by Letters Patent is set forth in the appended claims.

I claim:

1. In an envelope printing mechanism, the combination with a conveyor having a substantially vertical pick-up stretch and having pins at uniformly spaced intervals for engaging in the corners between the folded-over sealing flaps and the envelope backs to lift the envelopes out of stack formation and positively carry them away in properly timed, individualized relation, of a stack feeder for advancing the blanks in stack formation to the pick-up point of the pin conveyor comprising a stack conveyor along which the stacked envelopes are advanced in upright attitudes, an abutment in the stack path at the pick-up point against which the sealing flap of the leading envelope bears lightly, a density meter for measuring the stack density of the envelopes along a lower corner of the stack near the pick-up point, and mechanism responsive to the density meter to reduce the speed of the stack conveyor below a critical speed when a desired critical density is exceeded and to increase the speed of the stack conveyor to a predetermined, comparatively high speed above the critical speed when the critical density is not maintained.

2. In an envelope printing mechanism having a conveyor which includes a substantially vertical pick-up stretch and which is provided with pick-up pins at uniformly spaced intervals for engaging and pushing the envelopes to advance them positively in properly timed and spaced relation, a stack feeder for advancing the blanks in stack formation to the conveyor comprising a two-speed conveyor along which the stacked envelopes are advanced in upright attitudes toward the pick-up point, a light source disposed to project light between the lower corners of envelopes advanced by the two-speed conveyor as they near the pick-up point, a photoelectric cell responsive to the transmitted light, and mechanism responsive to the photoelectric cell for reducing the speed of the two-speed conveyor when a desired critical envelope density is exceeded and for increasing the speed of the two-speed conveyor when the critical density is not maintained.

3. In an envelope printing mechanism having a conveyor which includes a substantially vertical pick-up stretch and which is provided with pins at uniformly spaced intervals for engaging the corners between the folded-over sealing flaps and the envelope backs to advance the envelopes positively in properly timed and spaced relation, a stack feeder for advancing the blanks in stack formation to the conveyor comprising a two-speed conveyor along which the stacked envelopes are advanced in upright attitudes toward the pick-up point, a light source disposed to project light between the lower corners of envelopes advanced by the two-speed conveyor as they near the pick-up point, a photoelectric cell responsive to the transmitted light, electrical mechanism responsive to the photoelectric cell comprising an amplifier for the photoelectric cell output, a relay controlled by the amplified output and power mechanism controlled by the relay to reduce the speed of the two-speed conveyor when a desired critical envelope density

is exceeded, and to increase the speed of the two-speed conveyor when the critical density is not maintained.

4. A stack feeder for envelopes comprising, in combination, a stack conveyor for supporting envelopes on edge and advancing them in upright attitudes toward a pick-up point from which they are removed at a constant rate, mechanism for driving the conveyor continually at either one or the other of two predetermined speeds, the one too slow to maintain a critical density and the other too fast to maintain the critical density, and control mechanism for causing the two speed conveyor to deliver the envelopes to the pick-up point in a formation of predetermined density comprising a density meter for measuring the stack density of the envelopes near the pick-up point, and mechanism responsive to the density meter for causing the two-speed conveyor to be driven at the lower of said speeds when a desired critical density is exceeded, and for increasing the speed of the two-speed conveyor to the higher of said speeds when the critical density is not maintained.

5. In an envelope printing machine having an individualizing conveyor for advancing envelopes in predetermined, timed and spaced relation, in combination, mechanism for advancing blanks in stack formation toward a pick-up point at which they are picked up by the individualizing conveyor, comprising a feeding conveyor for advancing the envelopes in stack formation and delivering them at proper average frequency and density to meet the requirements of the individualizing conveyor, mechanism for measuring the density of the envelopes as they near the pick-up point, means for driving the feeding conveyor evenly at a predetermined speed less than that required to maintain the desired frequency of delivery, means for driving the feeding conveyor evenly at a predetermined speed greater than that required to maintain the desired envelope density, and mechanism responsive to said measuring mechanism to increase or diminish the speed of the stack conveyor as required to maintain the desired envelope density and an average rate of delivery equal to the requirements of the individualizing conveyor.

6. An envelope machine comprising, in combination, a conveyor having an upwardly traveling pick-up portion and having pins at uniformly spaced intervals for engaging in the corners between the folded over sealing flaps and the envelope backs to advance the envelopes positively in properly timed and spaced relation, mechanism for driving said conveyor at constant speed, a stack feeder for advancing the blanks in stack formation to the pick-up point of the pin conveyor comprising a two-speed conveyor along which the stacked envelopes are advanced in upright attitudes, a first constantly running transmission train including a slip clutch adapted to drive the two-speed conveyor at a speed lower than that required to produce the required average rate of envelope delivery and a desired, critical envelope density, a second transmission train adapted to drive the two speed conveyor at a speed higher than that required to produce the required average rate of envelope delivery and the desired critical envelope density, a clutch controlling the second transmission train, a light meter for measuring the envelope density of the stack as it approaches the pick-up point, and mechanism responsive to said light meter for controlling the last mentioned clutch.

7. A structure as set forth in claim 6 which further includes an infinitely adjustable variable speed drive through which both the transmission trains are driven from the mechanism which drives the pin conveyor.
